UNITED STATES PATENT OFFICE

CHARLES BRANDMAN, OF BOSTON, MASSACHUSETTS, ASSIGNOR TO EMERSON SHOE
MANUFACTURING COMPANY, OF ROCKLAND, MASSACHUSETTS, A CORPORATION OF MASSACHUSETTS

DESIGN FOR A STORE FRONT OR THE LIKE

Application filed May 21, 1929. Serial No. 31,324. Term of patent 7 years.

To all whom it may concern:

Be it known that I, CHARLES BRANDMAN, a citizen of the United States, residing at Boston, in the county of Suffolk and Commonwealth of Massachusetts, have invented a new, original, and ornamental Design for a Store Front or the like, of which the following is a specification, reference being had to the accompanying drawing, forming a part thereof.

In the drawing, Figure 1 is a front perspective view of a store front embodying my design; and Fig. 2 is a sectional view in diagrammatic outline on the line 2—2 of Fig. 1.

I claim:

The ornamental design for a store front or the like, substantially as shown.

CHARLES BRANDMAN.
